UNITED STATES PATENT OFFICE.

OSCAR GRAFF, OF PHILADELPHIA, PENNSYLVANIA.

SHOE LACING.

Application filed July 13, 1921. Serial No. 484,329.

To all whom it may concern:

Be it known that I, OSCAR GRAFF, a citizen of the United States, residing at Philadelphia, in the county of Philadelphia and 5 State of Pennsylvania, have invented certain new and useful Improvements in Shoe Lacings, of which the following is a specification.

This invention relates to improvements in 10 shoe laces and more particularly to an improved structure for high laced boots or shoes.

The primary object of the invention is to 15 provide a removable flap to which the laces are connected so that the flap may be quickly hooked to the body portion of the shoe when the laces are loose so that the laces need not be withdrawn from the lace eyelets.

One of the objects of the invention is to 20 provide a structure which will permit the shoe to be quickly removed from the foot without removing the laces from the eyelets, and which will also permit the shoe to be quickly fastened on the foot and the laces 25 tightened without the necessity of inserting the laces in the eyelets after they have once been placed in position.

Other objects of the invention will appear 30 upon consideration of the following detail description and accompanying drawings, wherein:—

Figure 1 is a perspective view of a shoe 35 constructed in accordance with my invention, and

Figure 2 is a perspective view showing the shoe open whereby the foot may be inserted in the shoe to have the boot laced thereon.

Referring to the drawing by numerals, 40 the shoe 1 is of the high lace type such as is worn by ladies during the winter season, although it will be obvious that the invention will be equally well adapted to be applied to any type of high lace boot. On one 45 marginal edge of the opening in the boot top is a strip 2 which is provided with the usual eyelet 3. This strip 2 is a permanent strip being rigidly and securely sewed to the boot and cannot be removed therefrom.

At the opposite side of the opening is arranged a removable strip 4 which is adapted 50 to be connected to the marginal edge of the opening by means of hooks and loops so that

the strip may be attached and detached. Adjacent this marginal edge is provided a series 55 of loops 5 which are adapted to receive hooks 6 mounted on the detachable strip, and the detachable strip is provided with eyelets which correspond to the eyelets in the permanent strip. This detachable strip is constructed so that when the hooks 6 are engaged with the loop 5, the strip will have the appearance of the permanent strip and therefore will not detract from the general appearance of the shoe. When the shoe 65 laces are inserted in the eyelets in both of the strips the same can be laced up in the ordinary manner so that the shoe can be tightened. When the shoe is to be removed it is merely necessary to loosen the shoe strings 70 without removing them from the eyelet whereupon the detachable strip may be disconnected by disconnecting the hooks from the loop and thus swing the laced portion open as shown in Fig. 2 of the drawing to 75 permit the user to remove her foot. When the shoe is put on, the hooks 6 will be caught in the loop 5 and the laces may then be tightened to firmly fasten the shoe in the desired manner.

Minor changes may be made in the details 80 of construction without departing from the spirit of the invention or the scope of the claims hereunto appended.

What is claimed is:

In combination with a high laced boot or shoe provided with an open front gap, each marginal edge of the gap being straight and extending throughout the length of the shoe, a strip removably fixed to one marginal edge 90 of the gap and provided with eyelets, a detachable strip provided with hooks, loops mounted on the marginal edge of the other side of the gap and adapted to be engaged by the hooks on the detachable strip, the 95 latter being provided with eyelets, and a shoe string adapted to be inserted in the eyelets for drawing the two strips together when the hooks are engaged with the loops.

In testimony whereof, I have affixed my 100 signature in the presence of two witnesses:

OSCAR GRAFF.

Witnesses:

HENRY KOCK,
JOSEPH SCHMIDT.
